(57) **CLAIM**

We claim the ornamental design for a post hole digger, as shown and described.

DESCRIPTION

FIG. 1 is a front perspective view of a post hole digger showing our new design in a closed configuration;

FIG. 2 is a front view of the post hole digger of FIG. 1, the opposing rear view being identical thereto;

FIG. 3 is a right side view of the post hole digger of FIG. 1, the opposing left side view being identical thereto;

FIG. 4 is a top view of the post hole digger of FIG. 1;

FIG. 5 is a bottom view of the post hole digger of FIG. 1; and,

FIG. 6 is a front perspective view of the post hole digger of FIG. 1 in an open configuration.

The dash-dash broken lines in the drawings illustrate portions of the post hole digger and form no part of the claimed design. The dot-dot-dash broken lines in the drawings define the bounds of the claim and form no part thereof. Shade lines in the drawing views show contour and not surface ornamentation of the claimed design.
